CLAUS LEVINSEN, OF BROOKLYN, NEW YORK

HEAT TRANSMITTER

Application filed May 16, 1930. Serial No. 453,034.

The device, the subject of this invention, is really a heat exchanger and is of the type employed for the cooling or heating by its passage through a structure, wherein is contained, or through which flows a fluid of a lower temperature for cooling, of higher temperature for heating.

I have designed this device for the purpose of cooling the lubricating oil of engines and particularly Diesel gas or turbine engines, and I am aware that it may be employed wherever it is desired to cool or heat a liquid or a gas that can be caused to circulate through my device.

An object of my invention is to construct a device in such a way that not only will it be simple from a mechanical point of view but exceedingly efficient and for the reason that every means is employed for increasing the cooling area, in a given space; also for filtering the liquid, and for preventing dangerous gas escaping.

Another object of the invention is to construct a device in such a manner that it may be repaired, if necessary, and without difficulty, and for that reason, the device is formed of a plurality of sections, any one of which may be removed without disturbing to any great extent, any other section, it being of course necessary to put the device temporarily out of service before a section is removed.

When a section is removed, the parts thereof may be disassembled, and a new part substituted readily and without serious complication, and in this way, I provide that the device may operate efficiently for a long period of time, and with a minimum of "shutdowns".

Another object of the invention is to so construct my device that I may take advantage of the so-called "counter-current flow" of liquids, which I believe to be the most efficient condenser practice.

With these objects in view, and others not

heretofore referred to, the following is what I consider the best means of carrying out my invention, and the accompanying drawings should be referred to for a complete understanding of the specification which follows.

In the drawings:—

Fig. 1 is a side elevation of my device.

Fig. 2 is an end view.

Fig. 3 is a sectional view of the device shown in Figs. 1 and 2, the section being taken on the lines 3—3 of Fig. 2.

Fig. 4 is a front elevation of a single section member.

Fig. 5 is a side elevation of a desired form of separator, and

Fig. 6 is a sectional view of a cap having a filtering means.

Similar reference numerals indicate like parts in all the figures where they appear.

At 1, I show an end element. This element is formed with a plurality of lugs, as shown at 2, 3, 4, 5, 6, 7, 8 and 9, in Fig. 2. This element is formed with a dome 10, projecting outward and beyond the plane of the body member 1. This dome is formed integrally with the member 1, which member may be considered a plate.

The lugs 2, 3, 6 and 7 receive pipes, as shown at 11, 12, 13 and 14. The pipes 12 and 13 may be considered oil circulation pipes, and the pipes 11 and 14 water circulation pipes. The oil will enter at 12, and pass out of the device at 13, and the water will enter at 14, and pass out of the device at 11, and it will therefore be seen that the oil and water are flowing through the device countercurrent to each other, the oil passing downward through the device, and the water upward therethrough, if for oil cooling.

At 15, 16, 17, 18, 19 and 20, I show securing bolts, and a plurality of bolts are employed for a purpose that shall appear later, and while it may appear that a great number of bolts are used, I do this for the reason that my device must be tight, and yet I

prefer not to use packing between the parts, but to bring the parts firmly together, metal to metal. This not only simplifies the construction, but materially aids in assembling or disassembling the structure.

At the other end, the left end, in Fig. 1, of the drawings, I provide another end plate, as shown at 23. This plate is, in all respects, similar to the plate 1, and is provided with a dome 24.

The separator member is of a shape similar to the member 25. In Fig. 3, the separators are not shown corrugated, and while they may be made with or without corrugations, I prefer that they be corrugated for the reasons set forth.

And now, when the device is assembled in the manner described, oil may be introduced in the direction of the arrow A, and will flow downward in alternate spaces, as indicated by the arrow O, to be discharged in the direction indicated by the arrow B. Water will be introduced through the pipe 14 and in the direction of the arrow C, and will flow upward in alternate spaces, as indicated by the arrow W, to be discharged through the opening 11, shown in Fig. 2.

While I have referred continually to oil and water, I, of course, desire it understood that any cooling or heating medium may be employed in lieu of the water, and any fluid or gas medium may have its temperature reduced or raised by causing it to pass through one of my devices, and in counter-relation to the passage of the cooling medium, or heating medium.

While I have described this device as a means for removing the heat from oil or other fluids, it will be just as readily employed for the purpose of imparting heat to oil, or other fluids, if such is desired.

In Fig. 6, I show a filtering cap. This cap is intended to be used as a substitute for either of the end members, 1 or 23, but would be placed where the oil enters my device, so that the oil will be filtered, before passing through my device.

While the dome 10 projects outward, exteriorly of my structure, the dome 24 projects inwardly and toward members, which I am about to describe.

Arranged between the plates 1 and 23, are a plurality of sections, and as each of these sections is of the same shape and size, and as each operates in an exactly similar manner to all other sections, I will describe the construction of only a single section, desiring it understood, however, that any number of sections may be introduced between the plates 1 and 23, the number being determined entirely by the desired capacity or operable efficiency of the completed device. Only a fraction of all the liquid passes between each segment.

Each section consists of a base member 25,

having a plurality of lugs formed integrally therewith, as shown at 26, 27, 28 and 29, and these lugs are so positioned that together, and with the pipe fittings already described, and separators, they form a passage or conduit throughout the device, and through which the oil and water are free to pass. As shown in Fig. 4, a portion of the base member 25 is cut away to produce a passage from the perforation in each lug to the center, two of these passages being arranged on one side of the member 25, and for a purpose that shall appear later.

At Fig. 5, I show a disc or separator member. This disc member may have a plurality of lugs formed integrally therewith. As shown in Fig. 5, this disc member, and in fact, all of the separators 30-31, may be corrugated for the purpose of increasing the effective area thereof.

The filtering cap is provided with an inlet passage 38, through which the oil enters—to be received into a distributing conduit 39, which conduit connects with a conduit 40 in the cap member 41. The oil passes interiorly of a filter, which may be a cylindrical member 42 having a screen 43 at the innermost end thereof. The spring 44 urges the filter upward on the supporting bolt 45. The oil passing through the filter and screen 43, now enters my device through the passage 46, and valve 47.

In Fig. 4, I show a section member, having a channel 48 produced therein. A perforation 49 allows water to pass into this channel, thus producing a water seal between each sectional member, which is desirable, if the device is to be used for ammonia, or other fugitive gases.

It will be understood that the size of all parts may be changed at will, to increase or decrease the capacity of the heat exchanger; that the number of intermediate units may be decreased or increased, and other modifications may be made within the scope of the appended claims, without departing from the principle, or sacrificing the advantages of this invention.

Having carefully and fully described my invention, what I claim and desire to secure by Letters Patent is:—

1. A heat transmitter, having means for increasing the effective area thereof, said means comprising a plurality of sections, a plurality of dome-shaped members associated with each said section and projecting thereinto, and end members, one said member having an outwardly projecting dome and the other said member having an inwardly projecting dome, and means for securing the whole in operative position.

2. A heat transmitter comprising a plurality of end members oppositely domed, a plurality of sectional members arranged therebetween, each said sectional member being

provided with lugs, having passages therethrough and transverse passages therein, separators between said sectional members, being provided with passages communicating from the first said passages in the lugs to the space between alternate pairs of separators.

3. A heat transmitter comprising a plurality of end members, each said end member being dome shaped and each said end member being provided with corrugations to increase the effective area thereof and a plurality of section members between said dome shaped members.
